MACHINE FOR REPAIRING KNITTED FABRICS

Filed April 12, 1930 2 Sheets-Sheet 2

UNITED STATES PATENT OFFICE

ALEXANDER C. PARLINI, OF WOODSIDE, NEW YORK, ASSIGNOR TO GOTHAM KNITBAC MACHINE CORPORATION, OF NEW YORK, N. Y., A CORPORATION OF DELAWARE

MACHINE FOR REPAIRING KNITTED FABRICS

Application filed April 12, 1930. Serial No. 443,649.

This invention relates in general to apparatus for repairing runs in knitted fabrics such as silk stockings.

One of the objects of this invention is the provision of improved apparatus for carrying out repairing operations in a rapid and efficient manner.

A further object of this invention contemplates a machine of this nature in which feeding heads having spacer wheels with different numbers of spacing teeth may be interchangeably mounted in the machine without requiring any adjustment of the machine with respect to timing.

15 A further object of the invention is to provide a detachable feeding head for such a machine, which is so constructed that when it is mounted in the machine, the feeding mechanism thereof will be positioned in exact alignment with the operating mechanism therefor and will perform its functions in the proper manner and without the necessity of making further adjustments of its operating mechanism.

20 These and other objects as will appear from the following disclosure are secured by means of this invention.

The invention resides substantially in the combination, construction, arrangement and 25 relative location of parts, all as will be more fully disclosed hereinafter and set forth in the appended claims.

Referring to the drawings:

Figure 1 is a side elevational view of the 30 complete machine with the detachable feeder head mounted therein and with a portion of the main standard broken away to show the interior mechanism.

Figure 2 is an enlarged view in side elevation of the detachable feeder head and showing the manner it is attached to an arm of the machine.

Figure 3 is an enlarged view in side elevation of the detachable feeder head showing a portion thereof and a portion of the arm to which it is attached, in section. This figure also shows the relative position of the needle bar assembly of the machine with respect to the detachable feeder head when it is in 45 operative position.

Figure 4 is a sectional plan view on the line 4—4 of Figure 2.

Figure 5 is a sectional view of Figure 2 on the line 4—4 looking in the direction of the arrows.

The run repairing machine of this invention involves generally the combination of elements described and claimed in United States Letters Patent No. 1,708,681 issued April 9, 1929 to Raymond L. Plumley, but 50 contains certain new improvements with respect thereto. In machine of the type disclosed in the above mentioned patent, there is provided a feeding head which is usually constructed as an integral part of one of the 55 projecting arms of the hollow standard which encloses the operating mechanism of the machine. Assembled in said feeding head is a spacer wheel which operates to space, the cross threads of the run to be repaired, and to feed said cross threads in spaced relation, step by step to the knitting needle which re-knits the run by looping each of said cross threads through the succeeding one as the fabric is advanced. The feeding 60 wheel assembled in the feeding head is designed and constructed so that it is only adaptable to space and feed cross threads of a run in fabric which are knitted of a certain 65 gauge.

If it is desired to use the machine for making repairs in a fabric of a different gauge of knitting, it is necessary to dismount the feeding mechanism from the feeding head and disassemble the same, and replace the spacer 70 wheel forming a part thereof, with a spacer wheel having the required number of teeth for properly spacing and feeding the cross threads of the different gauge fabric. It is 75 also necessary, when such a change of spacer 80 wheel is effected, to make certain adjustments of other working parts of the machine so that said parts will operate in proper timed 85 relation with respect to the operation of the substituted spacer wheel. In addition to 90 the above requirements it is necessary to re-time the movement of the spacer wheel with 95 relation to the movement of the latch needle when a new spacer wheel is incorporated in 100 the machine.

The particular object of this invention is to provide a machine of the above nature in which detachable feeding head assemblies having spacer wheels with different numbers of teeth may be interchangeably mounted in the machine without requiring any adjustment of the other operating parts of the machine.

A better understanding of the purposes 10 of this invention and the construction of the apparatus by means of which they are secured will be had by detailed reference to the drawing.

The machine is shown comprising a base 15 plate 1 having the integral vertical hollow standard 2 provided with the hollow projecting substantially parallel arms 3 and 4. Journaled transversely of the standard 2 is a rotatable shaft 4^a which may be driven by a 20 suitable electric motor (not shown).

Keyed to the shaft 4^a are two cams, one of which is indicated at 5. These cams actuate the levers 6 and 7. The cam 5 actuates lever 6. The other cam which actuates lever 7 is 25 in back of the cam 5 and is not apparent in the drawings. Pivots connected to the lever 6 is a lever 8 which is shown in dotted lines in Figure 1. The lever 8 is pivotally supported at 9 on the arm 4. The other end 30 of lever 8 is pivotally secured to the operating mechanism for actuating the spindle 10 in which the repair needle 11 is secured. It will be understood that the repair needle 11 35 has a hooked end and is provided with a latch.

Another lever 12 is pivotally secured to the lower end of lever 7 and in turn is mounted to reciprocate in the hollow arm 3 on the 40 pivot screws 13. The lever 12 has pivotally mounted at one end thereof, the pawl 19 which is adapted to be held against a ratchet wheel 20 of the feeder head.

A spring pressed vertically slidable rod 45 14 is also mounted in the end of hollow arm 4 and has secured to it a rotatable roller 15. The roller serves to hold the fabric being repaired against the feeding head 17 to cause it to firmly engage therewith. A spring finger 16 is also provided in the needle bar 50 assembly and is positioned in alignment with the path of the movement of the needle 11 and serves to hold the fabric being repaired firmly in place at the point of repair so that the cross threads of the run in the fabric are 55 held in proper spaced relation in the teeth of the feeder wheels positioned in the feeder head 17.

The feeder head of the machine with the feeding mechanism assembled therewith is 60 indicated generally at 17. In accordance with my present invention the feeder head instead of being integrally secured to the arm 3 of the machine is constructed as a separate unit and is adapted to be detachably secured to the end of arm 3. The construc-

tion of the feeder head and the manner in which it is secured to the arm 3 is as follows:

Referring particularly to Figures 3 and 5 of the drawings, the feeder head assembly comprises the side portions 21 and 22 which extend from an annular neck portion 23 and which are spaced apart so that the feeding mechanism may be mounted therebetween. The annular neck portion 21 is formed with a reduced extension 24 which is adapted to have a sliding fit in the annular recess 25 provided in the end of hollow arm 3 of the machine. The end 26 of arm 3 is adapted to abut against the shoulder 27. The shoulder 27 is so positioned that when the end of arm 3 70 abuts thereagainst the end of the operating arm 12 upon which the pawl 19 is mounted is in proper position to engage the ratchet wheel 20 of the feeding mechanism.

The reduced portion 24 of the annular neck 75 23 is provided with a screw threaded portion 28 adapted to receive therein the screw 29 which is formed with an eccentric head 30. The screw threaded portion 28 is also provided with an opening 31 (see Fig. 4) to receive the set screw 32.

The recessed portion 25 at the end of hollow arm 3 is split as at 33 (see Fig. 5) and is provided with the lugs 34 and 35 having the openings 36 there through which is adapted 80 to receive the screw 37. The head of screw 37 is provided with the lever 38.

The recessed portion 25 is also provided with a slot 38^a which is adapted to receive the head 30, of the screw 39 which is mounted in 100 the reduced portion 24 of the annular neck 23 of the feeder head.

The feeding mechanism which is mounted between the side portions 21 and 22 of the feeder head assembly, comprises combined 105 spacing and feeding wheels assembled into a unitary rotatable structure which is adapted to uniformly space apart the successive fabric threads which cross the run in the fabric to be repaired and to hold and feed the said spaced threads to the run repair needle. This mechanism is of the usual construction and consists of the following elements which are mounted between the side portions of the 110 feeder head in the following manner:

Journaled in the sides 22 and 23 on a short shaft 39 is a ratchet wheel 20 which lies between two parallel toothed or serrated spacer wheels 40 and 41. The ratchet wheel is made of less diameter than the spacer wheels and serves to hold them in predetermined spaced position. Lying on each side of the spacer wheels are the members 42 and 43 which have roughened surfaces to form a feeder wheel or 115 wheels which cooperate with the spring fingers 16 for the purpose of feeding the fabric being repaired at a predetermined rate to the needle.

In securing the feeder head assembly, the above described, to the arm 3 of the ma- 120 125 130

chine, the reduced extension 24 of the annular neck 23 of the feeder head is slid into the recessed portion 25 of the end of arm 3 until the end of arm 3 abuts against the shoulder 5 27 of the feeder head assembly. This will bring the pawl 19, positioned at the end of arm 12, in alignment with and so that it will engage the ratchet wheel 20 of the feeder mechanism. In sliding the feeder head assembly 10 into the recessed portion of the arm 3 the head 30 of screw 29 mounted on the reduced portion 24 is positioned so that it enters the slot 38^a in the recessed portion 25. The screw 29 is mounted in the reduced extension 15 24 at right angles to the feeding mechanism of the feeder head and the slot 38^a is located in the recessed portion of the arm 3 in such manner that when it receives the head of screw 29 therein, the feeder head will 20 be positioned so that the feeding mechanism will be correctly aligned with the pawl 19.

After the feeder head assembly has been positioned with respect to arm 3 and so that the pawl 19 correctly engages the ratchet 25 wheel 20, the screw 37, which engages the lugs 34 and 35 of the recessed portion 25 of arm 3, is tightened by means of the lever 38 and the feeder head is securely locked in position with respect to the machine.

30 By means of this construction it can be seen that feeder heads can be provided with spacer wheels with different numbers of teeth which are adapted to space and feed different gauge fabrics, and these feeder heads can be 35 quickly attached and detached from the machine and a proper alignment of the ratchet wheel of the feeding mechanism with the pawl on the operating arm 12 of the machine is accurately secured. Also the teeth on the 40 spaced wheels are accurately positioned in proper relative relation with the latch needle so that proper reknitting of the fabric is secured.

45 In order to maintain the proper vertical relation of the slot between the spacer wheels with the latch needle when the feeder head is assembled on the machine, each feeder head assembly when it is constructed is accurately adjusted by means of the positioning of the eccentric head 30 of the screw 50 29 in the slot 38^a on a master machine. The head of screw 29 is turned in the slot 38^a in the said master machine until the correct alignment of the slot between the spacer 55 wheels is arrived at and then the feeder head is removed from the master machine and the set screw 32 is tightened so as to fix the position of screw 29. Thereafter, when the feeder head assembly is attached to a machine it is unnecessary to make this adjustment of the spacer wheels.

60 It is to be understood that in the feeder head assemblies constructed in accordance with my invention, the distance between the shoulder 27 of the annular neck 23 and the

center of shaft 39 in the respective assemblies is the same within reasonable limits.

On the arm 12 of the machine I have positioned a pin 12^a which is so arranged adjacent to the pawl 19 that an extension 45 70 on the pawl will strike against said pin and prevent the pawl from having a too extreme upward movement when released from the ratchet when a change in feeding heads is being made. It will be understood that a too free movement upwardly by reason of the action of the spring 46 would possibly position the pawl in such a way that it would prevent the proper engagement of the pawl 75 with the ratchet wheel on a subsequent attachment of a new feeding head to the arm 3.

The advantages of the construction above described will, at once be apparent to those skilled in the art. I am of course, well aware that many changes in the details of construction and relative arrangement of parts will readily occur to those skilled in the art without departing from the principles of construction and operation of this invention and I do not, therefore, desire to be strictly limited to the disclosure as given for illustrative purposes, but rather to the spirit and scope of the invention as it has been defined in the appended claims.

90 What I seek to secure by United States Letters Patent is:

1. In an apparatus of the type described, the combination comprising a support having parallel extending hollow arms, a feeding head assembly having side portions with rotatable feeding means mounted therebetween, and an annular neck portion formed with a reduced extension, adapted to have a sliding fit with the end of one of said arms, a vertically 100 movable needle mounted in one of the arms of said support, means in said support for actuating said needle and said feeder means in timed relation with each other, means for detachably securing the reduced extension 105 of said feeder head to one of said arms, means on said reduced extension for angularly adjusting said feeder head to said support to align the feeding means in correct position with respect to the actuating means 110 therefor and with respect to said needle.

2. In an apparatus of the type described, the combination comprising a support, having parallel extending hollow arms, a feeding head assembly having side portions with rotatable feeding means mounted therebetween and an annular neck portion formed with a reduced extension which is adapted to have a sliding fit with the end of one of said hollow arms, a vertically movable needle 120 mounted in one of the arms of said support, means in said support for actuating said needle and said feeder means in timed relation with each other, means for detachably securing the reduced extension of said feeder 125

130

- head to one of said arms, means on said reduced extension for positioning the same with respect to said arm to bring the actuating mechanism for said feeder means in correct engagement therewith, and means on said reduced extension to angularly adjust said feeder head with respect to said arm to correctly align said feeder means with respect to said needle.
- 10 3. A detachable feeding head unit for a machine of the type described comprising an annular neck portion having spaced side portions extending therefrom, a feeding means rotatively mounted between said spaced side portions, means for attaching said feeding head to the machine and means mounted on said neck portion for angularly adjusting said feeder head when attached to said machine to correctly align the same with respect to the operating mechanism of the machine.
- 15 4. A detachable feeding head unit for a machine of the type described comprising an annular neck portion having spaced side portions extending therefrom and a reduced annular extension, feeding means rotatively mounted between said spaced side portions, means on said reduced annular extension for detachably securing said feeding head to the machine, means on said reduced extension for
- 20 adjusting the position of said feeding means with respect to its operating mechanism.
5. A detachable feeding head unit for a machine of the type described, comprising an annular neck portion having spaced side portions extending from one end thereof, feeding means rotatively mounted between said spaced side portions and comprising two spacer wheels having toothed peripheries, a ratchet wheel for operating said spacer
- 25 40 wheels, feeding wheels on the outside of each spacer wheel and a reduced annular portion extending from the other end of said neck portion adapted to be detachably connected with the machine.
- 45 6. A detachable feeding head unit for a machine of the type described comprising an annular neck portion having spaced side portions extending from one end thereof, feeding means rotatively mounted between said spaced side portions and comprising two spacer wheels having toothed peripheries, a ratchet wheel for operating said spacer wheels, feeding wheels on the outside of each spacer wheel and a reduced annular portion
- 50 55 60 extending from the other end of said neck portion adapted to be detachably connected with the machine and provided with means for angularly adjusting said feeder head with respect to the operating mechanism of said machine.

In testimony whereof I have hereunto set my hand on this 9 day of April A. D., 1930.

ALEXANDER C. PARLINI.
